UNITED STATES PATENT OFFICE.

HENRY T. DAVIS, OF SHERMAN, TEXAS.

QUILTING-FRAME.

SPECIFICATION forming part of Letters Patent No. 253,352, dated February 7, 1882.

Application filed March 31, 1881. (Model.)

To all whom it may concern:

Be it known that I, HENRY T. DAVIS, a citizen of the United States, residing at Sherman, in the county of Grayson and State of Texas, have invented Improvements in Quilting-Frames, of which the following is a specification.

The subject of my invention is a quilting-frame for use with sewing-machines, consisting of rollers adapted to stretch the quilt or cloth in customary manner and running in bearings in a frame which is mounted on a suitable stand, which adapts it for lateral movement to follow the feed of the sewing-machine, all as hereinafter described and claimed.

In the accompanying drawings, Figure 1 is a perspective view of the invention, showing its use in connection with a sewing-machine. Fig. 2 is a vertical section of the frame and its supporting-stand on the line 2 2, Fig. 3. Fig. 3 is a vertical section of the same on the line 3 3, Fig. 2.

A represents a stand of any ordinary construction, having an aperture, a, which may be provided with a pair of grooved pulleys, if desired, and receives a cord, B, carrying a weight, C, and attached to the plate or board D, which may be made of wood, and is adapted to slide freely on suitable bosses or rollers, 30 e, on the upper surface of the stand A.

To the board D are attached rigidly horizontal arms F F, which form part of the quilting-frame, having bearings f f for the reception of the stretching-rollers G G'. On the ends of 35 the stretching-rollers G G' are customary ratchet-wheels, H, in which pawls I engage.

J J are lateral stretching-hooks connected to elastic cords K.

The quilt is shown at Q.

40 L is a conical-pointed thumb-screw, which is turned up in the table A, forming a pivot on which the board D is supported, and turns under control of the feed, so as to form seams in curved lines, parallel or nearly so.

45 To adapt the stand to be readily moved, its legs are provided with casters or rollers M of any preferred form.

In operation the outer roller, G', is introduced beneath the arm of the sewing-machine, 50 so as to bring the desired line of seam near

the path of the needle. The sewing is then performed in the usual manner, the entire frame moving in a right line with the feed, and being held and guided by the operator as may be necessary. This done, the presser-foot and 55 needle are raised and the frame drawn back in the line of the feed and advanced laterally the proper distance for a new seam. The free mobility of the board D on the table A admits the described longitudinal and lateral movements with perfect ease and convenience, so as to run the seams as required and locate them at any desired distance asunder. When as many seams as may be convenient have been made in this way the quilt is moved in the 65 frame by detaching the lateral stretching-hooks J J and winding it upon the roller G' in the customary manner.

Whether used for producing straight parallel seams, as illustrated in Fig. 1, in which 70 case the pivot-screw L is withdrawn from contact with the frame, or for producing curved seams by the use of the pivot-screw turned up, as illustrated in Fig. 2, the cord and weight are useful in holding the frame steady in its 75 movements under the feed of the sewing-machine and restoring it automatically to its original position when the seam is completed and the needle and presser-foot lifted to release the work.

Having thus described my invention, the following is what I claim as new therein and desire to secure by Letters Patent:

1. The combination of the stand A and the quilting-frame movable thereon, having board 85 D, arms F, and rollers G G', substantially as described.

2. The combination of a stand, A, the quilting-frame having board D, arms F, and rollers G G', the cord B, and the weight C, substantially as set forth.

3. The combination of the stand A, pivot-screw L, and the quilting-frame having board D, arms F, and rollers G G', substantially as and for the purpose set forth.

HENRY T. DAVIS.
